Primary Examiner—Doris Clark

(57) CLAIM

The ornamental design for a doll clothing, as shown and described.

DESCRIPTION

FIG. 1 is a front elevational view of the doll clothing of the present invention;

FIG. 2 is a rear elevational view of the doll clothing of FIG. 1;

FIG. 3 is a right side elevational view of the doll clothing of FIG. 1; the left side view being a mirror image thereof;
FIG. 4 is a top plan view of the doll clothing of FIG. 1; and,
FIG. 5 is a bottom plan view of the doll clothing of FIG. 1. The broken lines showing a doll in FIGS. 1-5 are for illustrative purposes only and form no part of the claimed design.
